WAISTLINE TAPE

Edith F. Norman, Fox Lake, Ill.

Application March 5, 1953, Serial No. 340,605

3 Claims. (Cl. 33—13)

This invention relates to a waistline tape, and is particularly useful for home dressmaking. In home dressmaking, the waistline between a blouse and a skirt must be straight and at a proper height if the "home-made" look is to be avoided. Establishing this line is difficult. This same difficulty is encountered in establishing the waistline for the darts in the princess style (all in one) dress. This is also true in establishing the hip line for the "long torso" or middy type dress where a straight line for joining the skirt is wanted several inches below the normal waist line. The difficulty stems from a woman's using herself as a model. She either joins by basting the partly finished blouse and skirt as cut from the commercial pattern (waist lengths of which, i. e., from nape of neck to waist proper in back and from thorax to waist in front, never correspond with all figures of persons purchasing and employing these patterns), and after basting, slips the unfinished garment over her body for viewing and adjustment; or, she attempts by donning blouse to attach the skirt by pins. In so doing, she moves her arms and shoulders so as to draw the garment improperly around the waistline at the time she is doing the pinning. The result is a waistline which is not straight and which frequently does not rest properly above the hips.

Applicant's object is to provide a simple way of locating a waistline quickly and accurately when the woman is using herself as the model. Applicant attains the desired result by means of a marking tape. One tape of a durable material will be sold for inclusion in a sewing kit or as a notions item. An inexpensive tape made of a strong tissue paper will be offered for inclusion in dress patterns.

The two embodiments of the invention are shown in the drawings wherein:

Fig. 1 is a plan view of applicant's preferred tape;

Fig. 2 is a cross section taken on the line 2—2 of Fig. 1 but rotated 90 degrees;

Fig. 3 is a plan view of applicant's tissue paper tape to be included with patterns;

Fig. 4 illustrates how the locking tongue of Fig. 3 engages one of the openings in the tape;

Fig. 5 is a sketch of a woman showing how she stands when marking the tape around the waistline; and,

Fig. 6 is a plan view of applicant's tape with a chalked cord laced therethrough.

Continuing to refer to the drawings, the numeral 10 identifies a tape which may be made of a heavy paper or a glazed cloth. This pattern tape is of a fairly permanent nature and will be sold as a dressmaking aid in retail stores. One end of the tape has a tongue 12, formed therein, and lying on the surface of the tongue is a U-shaped annealed wire 14 which is held in position by glue or a transparent adhesive covering such as pressure sensitive adhesive tape. Along the body of the tape is a row of tear drop openings 16, 18. The end 20 of each of these openings is adapted to receive the tongue 12.

In using this tape, the woman slips on the blouse 22, referring to Fig. 5, and pins or buttons it across the front

so that it hangs properly. She then puts the tape 10 around and moves it up or down over the partially completed blouse until she has established that waistline which she desires. She bends the tongue 12 and the annealed wire 14 holds it as a hook. She engages the hook in a suitable opening 16 to hold the tape tight. The principal difference between the professional look and the "home-made" look resides in the straightness and definite location of the waistline. She can observe herself in a mirror until she gets this straight line position both front and back. She then takes a piece of chalk in her right hand and starting from the right center back runs it along the tape so that the chalk makes a mark on the blouse as it passes over each opening 16, 18, etc. She moves around to the right center front. Then she shifts the chalk to the left hand and repeats the operation on the left side. Thereafter, she removes the garment, bastes the next section, i. e., the skirt, into place, and trims, if necessary, any excess material.

The operation is the same for the princess type of garment, that is, one in which the blouse and skirt are in one piece, but it is necessary to form darts to establish the waistline. Here again, the applicant's tape establishes the waistline for the particular person for whom the garment is being made, and then the darts can be pinched in exactly at the waistline. In the "long torso" or middy type dress, the tape is put around the desired hip line, and the same operation is performed.

Returning to Figs. 1 and 2, the numeral 24 identifies a scoring which is on the outer surface of the tape, see Fig. 2. This scoring tends to keep the chalk centered on the tape as the woman moves the chalk around her waistline.

An alternative way of marking the waistline is to chalk a cord and thread it through the openings 16, 18, etc., before the tape has been adjusted to the proper position. This is illustrated in Fig. 6. The tape may be marketed without a hook on one end but laced with a cord slightly longer than the tape. Any compound harmless to cloth may be placed on the cord, but it must wipe off by friction. When the tape is in the desired position, the cord is drawn out, leaving a row of short chalk lines on the material.

Fig. 3 shows a tape 25 made out of a stout sheer paper and is intended to be incorporated in dress patterns. Instead of the metallic reinforced hook or tongue of the more permanent embodiment of the invention shown in Fig. 1, the tape has a T-shaped tongue 26 and triangular slots 28. When this T-shaped tongue 26 is seated in one of the slots 28, it has the configuration indicated by the solid lines 30 in Fig. 4.

Having thus described the invention, applicant claims:

1. A waistline tape comprising an elongated tape of flat flexible sheet material, a scoring in said sheet material parallel to its length and extending along its longitudinal median line, a plurality of spaced openings through said tape and intercepting said scoring, and a locking element at one end of the tape and engageable with one of said openings.

2. A waistline tape comprising an elongated tape of flat flexible sheet material, a tongue at one end of said tape, an annealed flat metallic member fastened to the surface of said tongue of said tape, a scoring in said tape parallel to its length and extending along its longitudinal median line, and a plurality of spaced openings through said tape and intercepting said scoring, said tongue constituting a locking element at one end of the tape and engageable with one of said openings.

3. A waistline tape comprising an elongated tape of flat, flexible sheet material, a deep scoring in said sheet material parallel to its length and extending along its longitudinal median line and forming a longitudinal valley

therein for centering the movement of a marking means such as chalk or interlacing chalk string, and a plurality of spaced openings through said tape and intercepting said scoring.
